UNITED STATES PATENT OFFICE.

GEORGE J. KAYE, OF DETROIT, MICHIGAN.

DESIGN FOR A TOY VACUUM DEVICE

60,041.

Specification for Design.

Patented Dec. 20, 1921.

Application filed January 3, 1921. Serial No. 434,813. Term of patent 3½ years.

To all whom it may concern:

Be it known that I, GEORGE J. KAYE, a citizen of the United States, residing at Detroit, in the county of Wayne and State of Michigan, have invented a new, original, and ornamental Design for a Toy Vacuum Device, of which the following is a specification, reference being had to the accompanying drawing, forming part thereof.

The figure is a perspective view showing the design of my toy vacuum device.

I claim:

The ornamental design for a toy vacuum device, as shown.

GEORGE J. KAYE.

Witnesses:

HERBERT C. KAYE,
KARL H. BUTLER.
